UNITED STATES PATENT OFFICE.

HENRY GAZAILLE, OF MANCHESTER, NEW HAMPSHIRE.

CASH-TRANSMITTER.

SPECIFICATION forming part of Letters Patent No. 298,077, dated May 6, 1884.

Application filed October 6, 1883. (No model.)

To all whom it may concern:

Be it known that I, HENRY GAZAILLE, a citizen of Great Britain, residing at Manchester, in the county of Hillsborough and State of New Hampshire, have invented certain new and useful Improvements in Cash-Transmitters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to devices for transmitting cash through a pneumatic tube from a salesman to a cashier, and vice versa, in stores or other places of business, of a class in which is employed a tube of uniform diameter, to receive a closely-fitting cash-carrier adapted to traverse it, one end of such tube being open and terminating at the cashier's desk, and its opposite end being practically closed and terminating at a point convenient of access to the salesman, an air-pump or its equivalent being connected with the tube for the purpose of inducing a current of air through the latter in either direction, and a suitable signal being combined with said tube and air-engine, to be operated by the cashier to notify the salesman his change is ready.

A prominent example of the class of transmitters to which my present improvements relate is shown in Letters Patent of the United States issued to myself on the 5th day of June, 1883. In the device as thus patented the distance to which the cash box or carrier can be impelled is restricted to a comparatively short range, for the reason that after the box is inserted in the tube and the tube closed against admittance of air repetitions of the motions of the pump only end in the box being driven back and forth in the same space, being retracted by the suction as far, or nearly so, as it was driven forward by the previous stroke of the pump. In my present improvements I employ a case capable of being hermetically sealed, and into this case I extend one end of the transmitting-tube, said case having a door to permit of insertion of the cash-box, and an air-inlet port governed by a double valve, so arranged that when the cash-box is inserted

in the tube, the door of the case closed, and the pump given one stroke, the valve can be opened to admit air to the case and tube to supply air for the next advance of the box, and allow a return-stroke to be imparted to the pump without retracting the cash-box, as in my patented device before named. The double valve enables the air-inlet to remain closed when but short distances are traversed; and in this latter event the construction shown in my patent is sufficient. It is only when considerable distances are to be traversed that the double valve is necessary.

The drawings accompanying this specification represent, in Figure 1, a side elevation, and in Figs. 2 and 3 opposite vertical sections, of a device embodying my improvements.

In said drawings, A represents a case which constitutes a "receiver," as it may be termed, of my transmitter, this case being of a size and shape to permit the cash-box to be inserted in the tube which terminates at one end in said case, a portion of said tube being shown at B.

D represents an opening in the front of the case A to permit of introduction into the tube B of the cash-box, while E represents the door of such opening, the said door E being constructed to close tightly against the case to prevent ingress of air.

F represents an air-inlet port in the back wall, G, of the case A, this port F being governed by a double valve, H, composed of two ordinary clapper-valves, a b, hinged at top to the wall G above the port F, and upon opposite sides of the latter, these two valves being held apart at an angle of thirty degrees, more or less, by an actuator, I, erected upon a bar, J, which is a thin upright plate sliding in a groove, d, in the bottom of the case, and arranged at right angles to the longest planes of the two valves. When the actuator I is pushed rearward, the valve a is permitted to open and close automatically, and the valve b held open, and vice versa.

The operation of this device is as follows: Supposing the salesman being about to send cash to the cashier, and the inner valve, a, being operative, while the outer one, b, is open and inactive, the door E of the case A is opened and the cash-box inserted by the salesman in the mouth of the tube B, when the

door E is closed. The salesman now gives one stroke, for instance, pushes down the pump-plunger of the air-pump connected with the case A, (a portion of the pipe connecting such pump with the case being shown at K,) which drives the box a certain distance within the tube, the valve a closing tightly and preventing escape of air by way of the port F. If the distance to which the cash-box is driven by this single stroke of the pump is sufficient to reach the cashier's desk, the cashier inserts the box, with the change in the open end of the tube near him, and the salesman, by a reverse stroke of the pump, brings the cash-box, with its change, back to himself; the valve b automatically closing and preventing inrush of air to the case. If, however, the cashier's desk is so remote from the salesman that one stroke of the pump will not drive the cash-box sufficiently far to reach said desk, the salesman simply lifts the pump-plunger, and again lowers it, thereby driving the cash-box a corresponding distance farther on its journey, the clapper-valve a opening to admit air and closing to prevent its escape. This allows air to enter the case and tube, and the return-stroke of the pump can be made without bringing back the cash-box, which remains at the point in the dispatch-tube B to which it was driven by the first or direct stroke of said pump. The salesman, if necessary, now gives a third direct stroke to the pump, with the same results—that is, drives the cash-box a farther distance in the dispatch-tube, and these motions are to be repeated until the box arrives at its destination. When the cashier places the cash-box, with the change, in his end of the tube, and notifies the salesman that his change is ready, the latter first reverses the position of

the two valves a b, by pulling the bar J forward—that is, holds the valve a open and permits the valve b to open and close automatically. The salesman now raises the pump-plunger, which exhausts the air from the tube B before the cash-box, and drives the latter toward the salesman, the valve b in the act automatically closing to maintain the case A air-tight. Should this single stroke of the plunger be insufficient to return the cash to the salesman, the latter pushes down the pump-plunger in readiness for a new stroke, the valve b opening automatically, and allowing escape of air from the case A, as otherwise the cash-box would be driven back by this movement of the pump-plunger. The salesman now lifts the pump-plunger, and thereby drives the cash-box a corresponding distance nearer to him, and these motions are repeated as long as is necessary.

I claim—

1. The combination, with a case or receiver, the dispatch-tube, and an air-pump connecting with said case and tube, of a valve or valves for admitting entrance of air to the case and dispatch-tube, and for closing the opening by which such air enters when the direct stroke of the pump is being made, substantially as explained.

2. In combination, the case A, with its door E, the dispatch-tube B, air-supply tube K, and double valve a b, arranged and to operate substantially as explained.

In testimony whereof I affix my signature in presence of two witnesses.

HENRY GAZAILLE.
